UNITED STATES PATENT OFFICE.

EDWARD E. FARMER, OF STRUTHERS, OHIO, ASSIGNOR TO THE YOUNGSTOWN SHEET & TUBE COMPANY, OF YOUNGSTOWN, OHIO, A CORPORATION OF OHIO.

DIE FOR RIVET AND NAIL MACHINES.

1,251,652.

Specification of Letters Patent.

Patented Jan. 1, 1918.

Application filed January 26, 1917. Serial No. 144,649.

To all whom it may concern:

Be it known that I, EDWARD E. FARMER, a citizen of the United States, residing at Struthers, in the county of Mahoning and State of Ohio, have invented a new and useful Improvement in Dies for Rivet and Nail Machines, of which the following is a full, clear, and exact description, reference being had to the accompanying drawings, forming part of this specification, in which—

Figure 1 is a front view partially in section, showing one form of my die in connection with a well known machine.

Fig. 1^a is a front view of the die block and dies on a larger scale.

Fig. 2 is a plan view thereof showing the header in connection therewith.

Fig. 3 is a transverse sectional view on the line III—III of Fig. 1^a.

Fig. 4 is an end view.

Figs. 5. and 6 are face views of the die members, and

Fig. 7 is a detail perspective view of the push-rod stop.

This invention relates to an improvement in combined die blocks and dies carried thereby for rivet or nail machines and is designed to provide a cheap and efficient self contained device of this character having a plurality of dies, one of which is arranged to shear off a piece of wire of a predetermined length and move the same laterally with relation to the main piece of wire, the die members being formed and arranged to

clamp the sheared piece of wire between them and hold it in position during the heading operation.

The precise nature of my invention will be best understood by reference to the accompanying drawings, which will now be described, it being premised, however, that various changes may be made in the details of construction and general arrangement of the parts, without departing from the spirit and scope of my invention, as defined in the appended claims.

Referring to the accompanying drawings, the reference character 2 designates the frame of one form of nail machine, which is arranged to receive my improved die and holder therefor. 3 designates a die-block having a securing flange 3^a for securing the die block to the machine and also having

fixed guides 4, and removable guides 5. These removable guides 5 are held in position by means of screws 6 and are arranged to be adjusted relative to the guides 4 by means of the adjusting screws 7. 8 are nuts on the screws 7 for locking the screws in their adjusted positions.

Slidably mounted between the guides 4 and 5 are the die members 9 and 10, each of which is provided with a semi-cylindrical recess 9^a and 10^a, respectively, which are arranged to register with each other to form approximately a cylindrical opening.

The die member 9 is provided with an opening for the reception of the bent end of a stop-rod 11, which stop-rod extends laterally through an opening in a stop-rod stop 12, which is secured to the die-block 3. The outer end of this stop-rod 11 is screw-threaded and 13 are nuts on the screw-threaded portion for limiting the inward movement of the rod 11 and the die member 9. 14 is an adjusting stop for the die member 9 and is provided with a lock-nut 15. 16 is a spring surrounding the screws 14 which bears against the die member 9 to normally hold it to the right. 17 is a clamp connected to the die-block 3 for retaining the rod 11 in position with relation to the die member 9.

Mounted on the frame 2 of the machine is a rocker arm 18, which is provided with a roller 19 adapted to be engaged by a cam 20 on a shaft 21, the arrangement being such that the rocker arm 18 is oscillated once during each rotation of the shaft 21. Connected to one arm of the rocker arm 18 is an adjustable pin 22 which is maintained in its adjusted position by a nut 23. The end of this pin 22 is tapered and is arranged to receive the recessed end of a push rod 24, the other end of which engages a recess in the die member 10. Connected to the die member 10 by means of a link 25 is a spring 26, the other end of which is connected to the rocker arm and which spring is arranged to maintain the die member 10, rod 24 and pin 22 in operating relation to each other.

Mounted within the die block 3 is a bushing 27 having an opening therethrough, which is arranged to register with the opening formed by the recess 9^a and 10^a in the die members 9 and 10 when said die members are moved to the right by means of

their springs 16 and 26. 28 is the wire from which the rivets or nails are to be formed and which is fed through the die block at predetermined intervals by any desired mechanism, and 29 is a header which is arranged to upset the end of a sheared blank in a manner hereinafter described.

The strip of wire is fed through the die-block a predetermined distance for each revolution of the machine, and after the predetermined amount of material has been fed through the die-block, the die members are moved to the left by means of the high portion of the cam 20 acting on the rocker arm 18. This action of the rocker arm will shift the die members to the left or to the position shown in Figs. 1^a and 2 to shear a blank of the proper length from the main piece of wire, move said blank in front of the header, 20 and clamp it between the die members 9 and 10. The header is then moved forward to upset the head of the blank and form the head of the rivet. After the header is moved out of engagement with the formed rivet, 25 the low portion of the cam 20 will be engaged by the roller 19 on the rocker arm, so that the spring 30 for returning the rocker arm to its initial position will act and shift the rocker arm to a position to permit the springs 26 and 16 to shift the die members 30 to the right and bring them into register with the opening in the bushing 27. The stop-rod 11 is adjusted with relation to the opening in the bushing 27 so that it will be 35 stopped short of the point where the recess therein is concentric with the opening in the bushing 27, while the die-member 10 will be moved to a point slightly beyond a point where its recess is concentric with the opening in the bushing. This is done in order 40 to provide a sufficient opening between the die-members to permit the rod or piece of wire 28 to be fed forward and eject the formed rivet.

45 The operation is then repeated for forming the next rivet.

The advantages of my invention result from the provision of a removable die block having adjustable guides for the movable die members, together with means for moving said die members relative to an opening in the die block for shearing a blank from the main piece of wire or rod and for clamping said blank in a position to be headed. 50 Also from the provision of adjustable means for stopping one of the die members relative to the other die member to form an opening of sufficient size between the die members to permit the rod from which the blanks are 55 formed to be fed forward and to eject the formed rivet.

I claim.

1. A device of the character described comprising a die block having an opening therethrough for the stock and adapted to

be removably secured to a machine frame, movable dies in the block, removable guides on said block for the dies, said dies being arranged to be moved laterally with relation to the opening through the block to shear a blank from the stock, a stop for limiting the movement of both dies in one direction, and means carried by the block to return the dies in position in front of the opening, substantially as described. 75

2. A device of the character described, comprising a die block having an opening therethrough for the stock and adapted to be removably secured to a machine frame, a removable bushing in the block, an opening in the bushing registering with the opening through the die block, movable dies in said block, removable guides on said block for the dies, said dies being arranged to be moved laterally with relation to the opening 80 through the bushing to shear a blank from the stock, a stop for the dies for limiting their movement in one direction, and spring means carried by the block to return the dies in position in front of the opening, substantially as described. 85

3. A device of the character described, comprising a die block having an opening therethrough for the stock and adapted to be removably secured to a machine frame, 95 movable dies in said block, said dies being arranged to be moved laterally with relation to the opening through the block to shear a blank from the stock, an adjustable stop carried by the die block for limiting the movement of the dies in one direction, and spring means carried by the block to return the dies in position in front of the opening, substantially as described. 100

4. A device of the character described, 105 comprising a die block having an opening therethrough for the stock and adapted to be removably secured to a machine frame, movable dies in said block, said dies being arranged to be moved laterally with relation to the opening through the block to shear a blank from the stock, an adjustable stop carried by the die block for limiting the movement of the dies in one direction, spring 110 means carried by the block to return the dies in position in front of the opening, and an adjustable stop carried by the block for limiting the return movement of one of the dies, substantially as described. 115

5. A device of the character described 120 comprising a die block having an opening therethrough for the stock and adapted to be removably secured to a machine frame, movable dies in said block, removable guides on said block for the dies, means for clamping the guides in position on the block, other means for adjusting the guides relative to the dies, said dies being arranged to be moved laterally with relation to the opening 125 through the block to shear a blank from the 130

stock, an adjustable stop carried by the block for limiting the movement of the dies in one direction, spring means for moving the dies into position in front of the opening, and a second adjustable stop carried by the block for limiting the movement of one of the dies in its return movement toward the opening.

In testimony whereof, I have hereunto set my hand.

EDWARD E. FARMER.
